UNITED STATES PATENT OFFICE.

ERNEST L. TEICH, OF NEW BRITAIN, CONNECTICUT, ASSIGNOR TO AMERICAN HARDWARE CORPORATION, OF NEW BRITAIN, CONNECTICUT, A CORPORATION OF CONNECTICUT.

LOCK INDICATING MECHANISM.

1,177,151.

Specification of Letters Patent. Patented Mar. 28, 1916.

Application filed August 15, 1914, Serial No. 856,896. Renewed January 31, 1916. Serial No. 75,467.

To all whom it may concern:

Be it known that I, ERNEST L. TEICH, a citizen of the United States, residing at New Britain, county of Hartford, State of Connecticut, have invented certain new and useful Improvements in Lock Indicating Mechanism, of which the following is a full, clear, and exact description.

This invention relates to lock mechanisms of a type employing a locking bolt freely operable from the inside of the lock, and operable from the outside of the lock by two differently constructed keys. In a lock of this type an indicator mechanism is provided in conjunction with means operable from the inside of the lock for dead-locking the door to which the bolt is applied, which means, in dead-locking position, coöperates with the indicator mechanism to place it in a telltale condition. The means controlled by one of the two keys referred to is arranged to dead-lock the door from the outside, and to place the indicator mechanism in telltale condition, the operation of the other of said keys having no effect on the indicator mechanism. These and other features will be more clearly seen from the following detailed specification, and from the accompanying drawings forming part thereof, and illustrating a preferable embodiment of the invention.

In these drawings: Figure 1 is a top plan view of a lock mechanism of the "unit" type, embodying the improvements of the present invention, the dead-bolt being shown in retracted position, and the indicator button in non-indicating position; Fig. 2 is a similar view with the dead bolt projected, and with the indicator button in telltale position; Fig. 3 is a reverse bottom plan view of the lock shown in Fig. 1; Fig. 4 is a rear end elevation of the lock mechanism shown in Fig. 1, the cover plate being broken away to disclose the interior; Fig. 5 is a transverse section on the line 5—5 of Fig. 1; Figs. 6 to 10 inclusive, show details of the lock mechanism.

Referring to the drawings by numerals, 1 indicates the inside escutcheon plate, and 2 the outside escutcheon plate, between which the lock frame is held by suitable connecting screws, in the usual manner employed in unit locks. This lock frame embodies the face plate 3^a, which has extending transversely therefrom spaced frame plates 3^b, these plates having suitable interconnecting

webs as shown. The frame plate 3^b, on the inside of the lock, carries an inwardly extending sleeve 1^a, for guiding the spindle 4^a of the inside knob 4, this sleeve extending through the inner escutcheon 1. The opposite frame plate 3^b carries a similar sleeve, which extends, in turn, through the outer escutcheon 2 for guiding the knob spindle 5^a of the outside knob 5.

A pivoted latch bolt 6 is carried by the face plate 3^a, and is pivotally attached thereto, the usual plunger 6^a guiding in a web of the lock frame. The bolt is normally projected through the coil spring 7 on said plunger operating between the frame web and the bolt head. The plunger 6^a terminates in a U-shaped yoke member 8, having laterally offset end portions 8^a positioned at opposite sides of the terminals of the knob spindles 4^a and 5^a. Below the latch bolt the face plate 3^a of the lock frame carries a pivoted or tilting stop-work button 9, in the form of a walking beam, one end of the button having pivoted thereto the forward end of a link 10, the rear end of which is bent downwardly and carries a pin 11 arranged, in one position on the walking beam button, to extend into a recess in the outer knob spindle 5^a, to lock said knob spindle against turning. This knob spindle, when not locked against turning by the pinion 11, is arranged to retract the latch bolt, and to this end has its inner end notched to receive and rotate therewith a roll-back 12, the opposite arms of which are arranged to engage the offsets 8^a of the yoke, to retract the latch bolt when the knob is turned. (See Fig. 5.) At the opposite side of the locking frame the knob spindle 4^a terminates, and, in turn, is slotted to receive a similar roll-back 13, which coöperates with the offsets 8^a at the side of the said offsets opposite the first roll-back 12. This roll-back is operable at all times by the inside knob to retract the latch bolt.

14 designates a dead-bolt arranged to be projected through the face plate 3^a of the lock frame, and having a shank 15 extending rearwardly in the lock frame, and suitably guided therein. Intermediate its ends, this shank has one side face cut away to provide a lug 16, which I term a retracting lug, and a shoulder 17 spaced thereon, which I may term a projecting shoulder (see Fig. 6). The forward or projecting movement of this

dead-bolt may be limited by suitable stop means, such as the cotter pin 19. This dead-bolt is moved to projecting and retracting position through the following mechanism.

6 At a point above the dead-bolt, a rock shaft 20 is journaled between the plates 3^b of the lock frame, one end journaling on a pin 21 carried by the frame plate, and the other end journaling upon the hub of certain 10 stop-work controlling mechanism operated through the said rock shaft, as will be later explained. At the end opposite the pin 21, the rock shaft 20 is provided with a cam arm 22, having on one face thereof a cam 15 23 constructed to extend between the lug 16 and the shoulder 17 of the shank of the dead-bolt, to engage these parts when the shaft 20 is rocked to retract and project the dead-bolt. This same end of the rock shaft 20 is recessed to provide a socket 24, within which is a further and inwardly extending squared socket 25, the first named socket journaling on the hub of a stop-work controlling arm 27. This same end of the rock 25 shaft is flattened on opposite sides as 26 (Fig. 8), and a leaf spring 26^a anchored in the frame engages these flat sides and tends to retain the shaft in bolt projected and retracted positions. At the end of the rock shaft opposite the cam arm 22, a bifurcated crank arm 28 is provided, extending from the shaft at an angle to the cam arm 22. The forward end of a pitman bar 29 is pivoted to this bifurcated crank, the bar extending 30 rearwardly and upwardly, and terminating at a point above the upper offset 8^a of the latch bolt yoke, (see Fig. 5). Adjacent this end of the pitman bar it is provided with a 35 depending right angular arm 30, which extends beneath and beyond the under face of the upper offset 8^a, and terminates in an upwardly extending hook or abutment 31. This abutment is positioned in the plane of the offset 8^a, and is adapted to be engaged 40 thereby in one position, and in one cycle of operation of the parts. A wear plate 32 is preferably attached to the rear end of this upper offset 8^a of the yoke. The under edge of the arm 30 is notched as at 33 (Fig. 5), 45 to receive a roll-back controlled by a key from the outer side of the lock, as will be hereinafter explained.

Attached to the rear end of the pitman bar 29 and depending therefrom, is an angular dog 34, the lower end of this dog being 50 positioned in line with the upper offset 8^a of the yoke. A coiled spring 35 is carried by the pitman bar and connected to the end of the dog 34, normally tending to move said 55 dog forwardly and against a pin 36, carried by the lower arm 30 of the pitman bar. As this dog is pivoted to the pitman bar, it may be moved independently of the bar and against the yoke offset to move it in a direction 60 to retract the latch bolt.

65

The outer knob 5 carries a cylinder lock mechanism (indicated in dotted lines in Fig. 1), the casing of this lock being designated by the numeral 37. This cylinder lock is of a peculiar construction and is specifically described and claimed in my co-pending application Serial No. 863,638, filed Sept. 26, 1914. For the purposes of the present disclosure it is sufficient to state that this cylinder lock employs the usual rotatable plug element, and inner and outer concentric sleeves. The end of the plug, in the direction of the lock mechanism, carries a disk 38, having its edge cut away to provide shoulders 39 and 40. This disk carries a sleeve 41, having a socket 42 therein for the reception of a roll-back spindle.

43 indicates the inner sleeve of the lock; 44 the outer sleeve, both sleeves terminating back of the disk 38 (shown in Fig. 9 of the drawings), there being a clearance space (not shown) between these sleeve ends and said disk. Seated against the ends of the sleeves, and back of the disk 38, is a sliding blocking piece 45 of a width equal substantially to the combined width of the sleeves, said block having thereon a pin 46, which extends out from the block at a point between the cutaway edge of the disk and the casing of the lock, and in the line of movement of the shoulders 39 and 40 of the disk 38 so as to be engaged by said shoulders when the disk is moved relative to the block. The inner sleeve, between its inner end and the outer face of the disk 38, carries a pin 47, designed to engage the block 45 when the inner sleeve is rotated, and the outer sleeve 44 carries a similar pin 48, likewise arranged to engage the blocking piece. The disk 38 carries on its outer and rear face a pin 49, arranged to engage the pin 47 of the inner sleeve, when the disk is rotated.

50 designates a roll-back spindle seating in the socket 42 of the plug sleeve, and extending through the outer knob sleeve 5^a and through the outer roll-back 12, to a point between the roll-backs 12 and 13. This spindle will rotate when the plug is rotated, the manner of rotation of said plug being governed by the key used. On the inner end of this spindle, adjacent and inwardly of the roll-back 12, I mount a roll-back 51, which is positioned in line with the pivoted dog 34 of the pitman bar. Rotation of this roll-back 51 to the left (Fig. 5) will engage said dog and move it, independently of the pitman bar, to engage the upper offset 8^a of the latch yoke to retract the latch. Adjacent and inwardly of this latch roll-back, the spindle 50 carries a dead-bolt roll-back 52, positioned in line with the notched edge 33 of the lower arm 30 of the pitman bar. The rotation of this roll-back 52, in opposite directions, moves the pitman bar to project and retract the dead-bolt.

The amount of rotation and direction of rotation of these roll-back members is governed by the particular key used. One key will be so bitted as to alone rotate the plug, 5 with its disk 38 and sleeve 41. The direction of rotation is limited to substantially a half turn in counter-clockwise direction (Fig. 5) or a half turn in a clockwise direction as seen in Fig. 9, the shoulder 39 of the 10 disk, engaging the pin 46 of the blocking piece 45, said piece being held against movement by the pin 48 of the outer sleeve, thereby stopping the disk and spindle 40 at the end of substantially a half revolution. The 15 outer sleeve 44 and also the inner sleeve do not rotate, and consequently the pin 48 of the outer sleeve forms a rigid abutment, preventing movement of the blocking piece 45 as aforesaid. Operation of the cylinder lock, 20 through one key, will, therefore, act to retract the latch bolt. This key would be used, of course, when the outer knob spindle is locked against rotation by reason of the stop-work button 9, and its associated parts, 25 as heretofore described.

Another and differently constructed key is arranged to operate the pitman bar to project and retract the dead-bolt. Such a key would be so bitted to operate the pin 30 tumblers of the cylinder lock, so that the inner sleeve 43 and the plug would rotate together. It will be seen from Fig. 9 of the drawings that this will permit the rotation of these parts for at least a full revolution, 35 from the position shown in Fig. 9 to the left or counter-clockwise and return, this representing dead bolt projecting and retracting movement and also latch-retracting movement. The last part of the return 40 movement corresponds to the latch-retracting movement by the first key heretofore described. As before stated, the roll-back 52 is in line with the notched end 33 of the pitman bar. Consequently, if the second key, 45 is inserted from the outside of the door in the cylinder lock, the spindle 50 may be turned for a full revolution in opposite directions, movement in a counter-clockwise direction (Fig. 9) operating to move the 50 pitman bar and rock shaft in a direction to project the dead-bolt. Movement of said roll-back in the opposite direction, by the same key, will engage the notch 33, to move said parts in the opposite direction to retract the dead-bolt and in the latter half of the return revolution will retract the latch bolt. The specific construction of this cylinder lock mechanism need not be further described, as it is fully described and specifically claimed in my co-pending application, 55 Serial No. 863,638 filed Sept. 26, 1914.

The operation of this dead-bolt, which, when projected, naturally dead-locks the door to which the lock is applied, is designed 60 to operate certain indicating mechanism lo-

cated on the outside of the lock. This indicating mechanism, in its preferable embodiment, comprises a button arranged to extend through and beyond the outer escutcheon plate, when in one telltale or indicating position. In the drawings, 53 designates the outer head of this indicator button, the shank thereof extending inwardly in the lock and through the frame plate thereof, its inner end 54 being conical in 70 shape to provide beveled sides. Intermediate its ends, this button member is provided with an annular groove 55. A spring 56, of the "hair pin" type, is anchored at its closed end to the frame plate 3^b (see Fig. 7), and has its arms engaging in this groove, and normally tends to move the button inwardly so that its head is flush, at least, with the outer face of the escutcheon plate. The adjacent edge of the rock shaft 20 is 75 provided with a beveled edge, shown best in Fig. 1 of the drawings, this beveled edge being designated 57, and extending toward the outer side of the lock. The conical end 54 of the indicator button is positioned 80 closely adjacent this edge of the rock shaft, so that when the rock shaft is oscillated to project the dead-bolt, this beveled edge 57 will act against the conical beveled end of the button to force the same outwardly 85 against the tension of its spring 56. In this position of the parts the head of the button will project beyond the escutcheon plate and will become an indication, or signal, 90 that the door is locked against operation by the ordinary means. Therefore, it will be evident that when the occupant of the room, to the door of which this lock is applied, desires to have the room undisturbed by, 95 say, for instance, the maid in the case of a hotel, the second key described will be utilized to project the dead-bolt from the outside, thereby dead-locking the door from the outside, and at the same time projecting the button indicator, by reason of the operation of the beveled edge of the rock shaft 100 thereagainst. The door may not be opened by the maid, who will have a key of the type first described, and the indicator button, by 105 its position, will announce the fact that this room is not to be entered. As before explained, the key of the first class can operate the plug of the cylinder lock for a half revolution in one direction only. With the dead-bolt projected, the notched edge 33 of the 110 pitman bar cannot be engaged by the roll-back 52 (which, of course, rotates with the spindle 50 and latch roll-back 51), because a complete revolution on the part of this roll-back 52 is necessary to engage such 115 notch and the spindle may only be rotated a half revolution through the key of the first class. Where a key of the second class is used, however, a complete revolution may be given the spindle to bring the roll-back 52 120

125 130

into engagement with the notch 33, so that the dead-bolt may be retracted.

Means are provided for projecting the dead-bolt from the inside of the lock. This means, takes the form of a thumb turn 58, whose spindle extends through the escutcheon plate and through the aperture of the stop-work controlling member 27, and thence into the squared socket 25 of the rock shaft, 10 coupling the thumb turn to the rock shaft, and also coupling the stop-work controlling member to the rock shaft. By means of the thumb turn, the rock shaft may be oscillated to project and retract the dead-bolt in 15 the same manner in which it is operated through the key controlling means heretofore described. It will, of course, be understood that when the rock shaft 20 is oscillated in the direction to retract the dead-bolt, its beveled edge 57 will move its high point away from the conical end 54 of the indicator button, so that the spring of said button may move it inwardly to non-indicating position.

25 I have heretofore described a specific embodiment of my invention, but desire it understood that the same is susceptible of variation in construction and in relative arrangement of the parts, within the spirit of 30 the invention and the scope of the appended claims. Also, I desire it understood that such parts of my invention as are herein shown and are also described, and are not claimed herein, are specifically described 35 and claimed in my co-pending applications Serial Nos. 863,637 and 863,638, both filed September 26, 1914.

What I claim, therefore, and desire to secure by Letters Patent, is:—

40 1. In a lock, a bolt, a knob at the inside of the lock for operating the same, other means at the inside of the lock for dead-locking the door to which the lock is applied, an indicator at the outside of the lock associated with the said dead-locking means and 45 arranged to be operated thereby when the door is dead-locked from the inside to indicate dead-locking of the door, a key for dead-locking and unlocking the door from 50 the outside with means for operating said indicator by the operation of said key to indicate dead-locking of the door.

55 2. In a lock, a bolt, a knob at the inside of the lock for operating the same, other means at the inside of the lock for dead-locking the door to which the lock is applied, an indicator at the outside of the lock associated with the said dead-locking means and 60 arranged to be operated thereby when the door is dead-locked from the inside to indicate dead-locking of the door, a key for dead-locking and unlocking the door from the outside with means for operating said indicator by the operation of said key to indicate dead-locking of the door, and a dif-

ferent key for unlocking the door without operating said indicator.

3. In a lock, a latch bolt, a knob at the inside of the lock for retracting said latch bolt, a knob at the outside of the lock for 70 retracting the same, means for locking said outside knob against latch retracting movement, means controlled by a key for retracting said latch bolt from the outside of the lock when said outside knob is locked, a 75 dead bolt, means at the inside of the lock for operating said dead-bolt, an indicator at the outside of the lock associated with the aforesaid dead-bolt operating means and arranged to be operated thereby when said 80 means is operated from the inside of the lock, and means controlled by a second and different key and operable from the outside of the lock to operate said dead-bolt and including means arranged to operate said in- 85 dicator.

4. In a lock, a latch bolt, a knob at the inside of the lock for retracting said latch bolt, a knob at the outside of the lock for retracting the same, means for locking said outside knob against latch retracting movement, means controlled by a key for retracting said latch bolt from the outside of the lock when said outside knob is locked, a 90 dead-bolt, means at the inside of the lock for operating said dead-bolt, an indicator at the outside of the lock associated with the aforesaid dead-bolt operating means and arranged to be operated thereby when said 95 means is operated from the inside of the lock, and means controlled by a second and different key and operable from the outside of the lock to operate said dead-bolt and including means arranged to operate said in- 100 dicator, said second key being also operable to retract said latch bolt.

5. In a lock, a latch bolt, a knob at the inside of the lock for retracting said latch bolt, a knob at the outside of the lock for retracting said bolt, means for locking said outside knob against latch retracting movement, means controlled by a key from the outside of the lock for retracting said latch bolt independently of said outside knob, a 110 dead-bolt, means operable from the inside of the lock for projecting and retracting said dead-bolt, an indicator at the outside of the lock arranged for projection and retraction, means operable by said dead-bolt operating means for operating said indicator, means controlled by a second key from the outside for projecting and retracting said dead-bolt, said means including indicator operating means, said second key being also operable to retract said latch bolt.

6. In a lock, a bolt, a knob at the inside of the lock for operating said bolt, other means at the inside of the lock for dead-locking the door to which the lock is applied, an indicator at the outside of the lock arranged 130

for projection and retraction, means operable by said dead-locking means to operate said indicator means to indicate dead-locking of the door, and means operable by a key 5 from the outside of the lock to lock and unlock said door, with means controlled by said key for operating said indicator to indicate dead-locking of the door.

7. In a lock, a latch bolt, a knob at the inside of the lock for retracting said latch bolt, a knob at the outside of the lock for retracting said bolt, means for locking said outside knob against latch retracting movement, means controlled by a key from the outside of the lock for retracting said latch bolt independently of said outside knob, a dead-bolt, means operable from the inside of the lock for projecting and retracting said dead-bolt, an indicator at the outside of the lock arranged for projection and retraction, cam means operable by said bolt operating means for operating said indicator, means controlled by a second key from the outside for projecting and retracting said dead-bolt, 20 said means including indicator operating means, said second key being also operable to retract said latch bolt.

8. In a lock, a latch bolt, knobs at the inside and outside of the lock for independently retracting said latch bolt, means for locking the outside knob against latch retracting movement, means controlled by a key from the outside of the lock for retracting said latch bolt independently of said outside knob, a dead-bolt, a rock shaft with means controlled thereby and operable by oscillation thereof to project and retract said

dead-bolt, means operable from the inside of the lock for oscillating said rock shaft, means controlled by a second key from the outside of the lock for oscillating said rock shaft and for retracting said latch bolt, an indicator member at the outside of the lock arranged for projection and retraction, with means controlled by the oscillation of said 45 rock shaft for operating said indicator.

9. In a lock, a latch bolt, knobs at the inside and outside of the lock for independently retracting said latch bolt, means for locking the outside knob against latch retracting movement, means controlled by a key from the outside of the lock for retracting said latch bolt independently of said outside knob, a dead-bolt, a rock shaft with means controlled thereby and operable by 50 the oscillation thereof to project and retract said dead-bolt, means operable from the inside of the lock for oscillating said rock shaft, means controlled by a second key from the outside of the lock for oscillating said 55 rock shaft and for retracting said latch bolt, an indicator member at the outside of the lock arranged for projection and retraction, said indicator member having at least two telltale positions, with means normally 60 tending to hold said member in one of said two positions, and means controlled by the oscillation of said rock shaft in bolt projecting direction for moving said indicator into a second telltale position.
